MULTIPLE AERIAL SWITCH

Charles E. Gerhard, Philadelphia, Pa., assignor
to Philco Radio & Television Corporation, Phil-
adelphie, Pa., a corporation of Delaware

Application October 10, 1935, Serial No. 44,458

6 Claims. (Cl. 250—9)

This invention relates to electrical signaling systems and, more particularly, to radio receiving systems wherein it is desired to use one of a plurality of radio sets with a single antenna and 5 to automatically connect only one radio receiving set to the antenna at any one time.

One object of the invention is to provide a novel system by means of which an antenna may be connected automatically to a radio receiver when 10 the receiver is turned on or energized and the antenna may be disconnected automatically from the receiver when the receiver is turned off or deenergized.

Another object of the invention is to provide 15 a compact device which may be readily connected electrically to an antenna and to a radio receiving set and by means of which the above stated result may be accomplished.

The invention is particularly adapted for use 20 in any instance where it is desired to use a plurality of radio receiving sets with a single antenna. For example, in stores or other places, where it is desired to demonstrate radio receivers using a single antenna for a plurality of receivers, it is possible by means of the present invention 25 to selectively connect any one of the radio receivers to the antenna automatically by merely turning on the radio receiver to be demonstrated, thus eliminating the necessity of several switching 30 operations or of making electrical connections. The invention is also adapted for use in homes where two or more radio receivers are used and it is desired to use a single antenna for the several 35 receivers. These particular adaptations and others will be more clearly apparent as the description proceeds.

The invention may be clearly understood by 40 reference to the accompanying drawing wherein there is illustrated a single preferred embodiment of the invention.

In the drawing:

Fig. 1 is a diagrammatic illustration of the 45 electrical system provided by the invention;

Fig. 2 is a front face view of the automatic 45 switching device provided by the invention;

Fig. 3 is a rear view of the mechanism of the 50 device with the back of the casing or housing removed; and

Fig. 4 is a sectional view of the device taken 55 along line 4—4 of Fig. 3.

Referring particularly to Fig. 1 of the drawing, there is shown an antenna 1 and a conventional transmission line 2 therefor. Conventional radio receiving sets are shown at 3 and 4, two such sets 55 being illustrated for the purpose of disclosure of

the invention. It will be understood, however, that any number of radio receiving sets may be employed. A suitable source of electrical energy is illustrated at 5, which source may be the conventional current supply line of a building such 5 as a store, dwelling, etc. In accordance with the invention, there is provided a device 6 associated with each of the radio receivers, as will be described in detail hereinafter.

As is well known, a radio receiver is usually 10 energized by some electrical supply source which may consist of batteries or any other conventional source. The energization of the radio receiver is controlled by a switch at the receiver. In the illustration of Fig. 1, the energizing switches of 15 1, the radio receivers 3 and 4 are shown, respectively, at 7 and 8. The receivers are actuated by high frequency signals picked up by the antenna 1, which signals build up voltages across the tuning units of the radio receivers, such units 20 being shown at 9 and 10, respectively. In a conventional radio receiver, the tuning unit may comprise an inductance or radio frequency transformer. For reception of signals in the broadcast band, it is customary to design this unit so that 25 it has relatively high inductance. For reception of signals in the short-wave bands, however, the said inductance is materially reduced. Thus, in one case the unit presents high impedance to signals in the broadcast band, while in the other 30 case, the unit presents low impedance to signals in the broadcast band. Thus, if the radio receiver 3 were adjusted to receive signals in the broadcast band and if the radio receiver 4 were adjusted to receive signals in the short-wave band and if 35 the two receivers were both connected to the same antenna, the tuning unit 9 of receiver 3 would be effectively short-circuited by the tuning unit 10 of receiver 4, and the reproduction of signals in the broadcast band by the receiver 3 would 40 be deleteriously affected. Likewise, even if both of the radio receivers were adjusted to receive signals within one frequency range and even if both of the tuning units 9 and 10 had substantially the same inductance, nevertheless the performance of each set would be materially affected 45 by the presence of the other set. For this reason, it has been customary, when using a plurality of radio receivers, to manually disconnect all of the receivers from the antenna except the one being 50 used or demonstrated. By means of the present invention, this may be accomplished automatically by the actuation of the conventional energizing switches 7 and 8.

The devices 6 shown in Fig. 1 are identical and 55

these devices, as well as the parts thereof, are designated by corresponding reference characters. A description of one of these devices and its cooperative association with the other elements of the system will suffice. The device comprises essentially a relay 11 having an energizing winding 12 and an armature 13. The winding 12 is connected in series in the energy supply circuit 14 of the radio receiver. Thus, the winding 12 is connected in series with the energizing switch at the receiver. The armature 13 comprises contacts 15 and 16 which are adapted to close the antenna lead-in circuit 17. The contacts 15 and 16 are normally maintained in opened position, as shown, by a spring 18, the armature being pivoted at the point 19.

It will be seen that closure of switch 7, for example, to energize the radio receiver 3 will, at the same time, energize the relay causing the contacts 15 and 16 thereof to close and thus connecting the receiver 3 to the antenna. The relay winding is designed to present negligible impedance to the energizing current, so that substantially full line voltage is applied to the receiver. When the switch 7 is opened to deenergize the receiver, the relay is automatically deenergized and the spring 18 causes the contacts 15 and 16 to open, thus automatically disconnecting the receiver from the antenna. In the same manner, the receiver 4 is automatically connected to the antenna when the switch 8 is closed and is automatically disconnected from the antenna when the switch 8 is opened. As stated above, any number of radio receivers may be used with the antenna, each receiver having associated with it a device 6, as illustrated, so that any one of the receivers may be automatically connected to the antenna and disconnected therefrom.

The device 6 preferably takes the form of a single compact unit having suitable electrical connectors to facilitate connection of the device to the associated elements or apparatus. This will be understood from the following description of the preferred form of the unitary device.

In the illustration of Fig. 1, radio receivers have been shown connected to the antenna 1 through the units 6 by means of the transmission line 2 which preferably comprises a low impedance line whose conductors are twisted as illustrated. Such a transmission line serves to reduce noise interference which might be picked up by the antenna lead-in. While this arrangement is preferred, it will be understood that any conventional antenna and lead-in which may comprise one or more wires, may be used. It will be noted also that the electrical connections to the radio receivers are shown as comprising twisted conductors and, while this is preferred, it is not necessary. Furthermore, it is generally desirable to separate the high frequency signal leads from the power leads.

The relay switches comprising contactors 15 and 16 should preferably be such as to form good contact of low resistance when the switches are closed and the switches should have very low inter-element capacity when open so that they will not act as a short-circuit to the high frequency short-wave signals.

Referring now to Figs. 2 to 4, the device 6 preferably comprises a two-part casing or housing having a front section 20 and a box-like back section 21 removably associated with the front section. A conventional plug receptacle 22 is mounted upon the front section of the casing and is adapted to receive the usual plug which is attached to the power supply leads of a radio

receiving set, thus connecting the radio set to the device 6. Insulated terminals 23 and 24 are also mounted upon the front section 20 and are adapted to receive the leads from the antenna transmission line or lead-in.

As shown more clearly in Figs. 3 and 4, a pair of inverted U-shaped brackets 25 and 26 are attached to the front section 20 of the casing, the receptacle 22 being secured to these supports and insulated therefrom by means of the plate 27 formed of insulating material. At the rear of the supporting brackets 25 and 26, there is attached a similar plate 28 of insulating material to which are secured terminals 29 and 30 having prongs 31 and 32 adapted for insertion in the usual outlet receptacle or convenience outlet. The prongs 31 and 32 extend through openings in the back section.

A supporting bracket 33 is mounted upon the brackets 25 and 26 and serves to support the elements of relay 11. The coil 12 of the relay is secured to the lower part of bracket 33 and the coil in turn supports insulating plate 34 which carries stationary contacts 35 and 36.

The relay armature comprises a plate 37 which is pivotally mounted upon bracket 33 at the point 19. Plate 37 carries an insulating member 38 which, in turn, carries the movable contact arms 15 and 16 above mentioned. These contact arms are normally maintained out of engagement with the stationary contacts 35 and 36 by the spring 18, above mentioned, which is secured between the armature plate 37 and the bracket 33.

From the illustration of Fig. 1, it will be seen that the prong 31 is connected to one extremity of the relay winding 12, the other extremity of the winding being connected to one of the contacts of the plug receptacle 22. The prong 32 is connected directly to the other contact of receptacle 22. Thus the relay winding, which presents low impedance to the energizing current, is connected serially in the power supply circuit of an associated receiver when the prongs 31 and 32 are inserted in a power supply outlet and when the plug attached to the power supply leads of the receiver is inserted in receptacle 22. The terminals 23 and 24 are connected electrically to the contact arms 15 and 16, while the stationary contacts 35 and 36 have electrical conductors connected thereto which extend through an opening 39 in the front face of the device in the form of a two-conductor cable 40. These conductors may be connected to the terminals provided on the radio receiving set for the antenna.

It will be seen that this device is compact and adapted for convenient use. By simply removing the box-like back section 21 of the casing, the various parts of the device are exposed and may be readily replaced whenever necessary. Moreover, the two sections of the casing may be held together by two screws, the front section having flanged side edges which overlap the sides of the back section. A screw on each side secures the back section to said flanges.

Although it is capable of various usages as above mentioned, the invention is particularly adapted for use in stores in the demonstration of radio sets to prospective buyers. With a plurality of radio sets connected to a single antenna through the devices 6, as illustrated in Fig. 1, the demonstrator or salesman may automatically connect any one of the radio receivers to the antenna by simply turning the receiver on in the usual fashion. Moreover, only that set which is turned on is connected to the antenna, so that

the proper demonstration of the particular set may be given. Thus, there is eliminated any necessity for the demonstrator or salesman to make any other electrical connections in order 5 to demonstrate the various radio sets.

5 In the sale of any article, it is desirable that the interest of the prospective buyer be constantly maintained and this requires uninterrupted contact of the salesman with the buyer. If the 10 radio set salesman is handicapped by having to make electrical connections, in order to demonstrate various sets to a customer, during his sales efforts, the interest of the customer is quite apt to lag and a sale, which would otherwise have 15 been effected, might be lost. By means of the present invention, the salesman or demonstrator enjoys uninterrupted contact with the customer and is better able to demonstrate various radio receiving sets.

20 It will also be seen that the invention is highly desirable and advantageous in any instance where it is desired to use a plurality of radio receivers with a single antenna. While the invention is directed particularly to radio receivers, 25 it will be understood that it is applicable in any case where a plurality of signal receiving devices are employed. Although the invention has been illustrated in a preferred specific form, it will be understood that it is not thus limited and may 30 be practiced with various modifications such as fall within the scope of the appended claims.

I claim:

1. In an electrical signaling system, a source 35 of electrical signals, a plurality of signal receiving devices, means for supplying electrical power to each of said signal receiving devices, and means associated with each of said devices and controllable by the power-supply means thereof, for selectively connecting a signal receiving device to said source when said device is energized and for disconnecting said source from said device when said device is deenergized.

2. In a radio receiving system, an antenna for collecting high frequency signals, a plurality of 45 radio receivers, means including a switch for supplying electrical power to each of said receivers, and means associated with each of said receivers and controllable by the power-supply means thereof, for selectively connecting a receiver to 50 said antenna when said receiver is energized and for disconnecting said antenna from said receiver when said receiver is deenergized, said last means comprising a relay having an energizing winding connected in series with said switch, 55 and electrical contacts controlled by said winding and connected in the antenna lead-in of the associated receiver.

3. A device for use with a signal receiving device to enable the connection of said receiving 60 device at will to a source of electrical signals, comprising a casing, a pair of contact prongs extending from said casing for insertion in an outlet receptacle, a two-contact receptacle on said casing adapted to receive a plug on a conductor cord 65 connected to power supply terminals on said receiving device, means within said casing connecting one of said prongs to one of said receptacle contacts, a relay within said casing comprising an energizing winding connected between the 70 other of said prongs and the other of said re-

ceptacle contacts, and circuit means within said casing controllable by said relay for connecting said source to said receiving device when the latter is energized and for disconnecting the source from the receiving device when the latter is de- 5 energized.

4. A device for use with a signal receiving device to enable the connection of said receiving device at will to a source of electrical signals, 10 comprising a casing, a pair of contact prongs extending from said casing for insertion in an outlet receptacle, a two-contact receptacle on said casing adapted to receive a plug on a conductor cord connected to power-supply terminals on said receiving device, means within said casing connecting one of said prongs to one of said receptacle contacts, a relay within said casing comprising an energizing winding connected between the other of said prongs and the other of said receptacle contacts, a pair of terminals on said 15 casing to which a transmission line from said source may be connected, a pair of conductors extending from said casing for connection to signal input terminals on said receiving device, and means within said casing controllable by said relay for connecting said terminals to said conductors when the receiving device is energized and for disconnecting said terminals from said conductors when the receiving device is deenergized. 20

5. A device for connecting a signal receiving device at will to a source of electrical signals, 25 comprising a casing, a pair of input elements on said casing adapted to be connected across a power-supply source, a pair of output elements on said casing adapted to be connected to the power-supply portion of said receiving device, means within said casing connecting one of said input elements to one of said output elements, a relay within said casing comprising an energizing winding connected between the other input element and the other output element, and circuit means within said casing controllable by said relay for connecting said source to said receiving device when the latter is energized and 40 for disconnecting the source from the receiving device when the latter is deenergized. 45

6. A device for connecting a signal receiving device at will to a source of electrical signals, 50 comprising a casing, a pair of input elements on said casing adapted to be connected across a power-supply source, a pair of output elements on said casing adapted to be connected to the power-supply portion of said receiving device, means within said casing connecting one of said input elements to one of said output elements, a relay within said casing comprising an energizing winding connected between the other input element and the other output element, a pair of 55 terminals on said casing to which a transmission line from said source may be connected, a pair of conductors extending from said casing for connection to signal input terminals on said receiving device, and means within said casing controllable by said relay for connecting said terminals to said conductors when the receiving device is energized and for disconnecting said terminals from said conductors when the receiving device is deenergized. 60
